Specification of Letters Patent. Patented Aug. 19, 1913.

Application filed August 14, 1912. Serial No. 715,065.

To all whom it may concern:

Be it known that I, EGIDIO MERCANDELLI, a subject of the King of Italy, residing at Amedee, in the county of Lassen and State 5 of California, have invented certain new and useful Improvements in Horseshoes, of which the following is a specification, reference being had therein to the accompanying drawing.

10 This invention relates to horse shoes and the principal object of the invention is to provide a novel form of horse shoe which will prevent the horse interfering and thereby cutting his fetlocks.

15 With the above object in view the invention consists in general of certain novel constructions as will be hereinafter set forth.

In the drawings:—Figure 1 is a side elevation of a horse shoe constructed in accordance with this invention. Fig. 2 is a plan view thereof taken from the underside. Fig. 3 is a rear elevation thereof. Fig. 4 is a view of the lower portion of a horse's leg showing the shoe applied thereto.

20 25 In carrying out the invention there is provided a horse shoe having a body portion 10, one side, as at 11, is of the usual shape common to horse shoes, while the other side is so formed that the curvature is substantially uniform throughout on the inside as at 12. The side 12 is intended to be the inside of the horse shoe and from the bottom thereof extends a projection 13 which slopes gently downward from the toe and ends in 30 an abrupt shoulder 14. Behind the shoulder 14 the usual nail groove 15 and nail holes 16 are provided, and around what may be termed the normal portion of the shoe is provided the usual nail groove 17 and nail 35 holes 18. There is also provided an upstanding triangular extension 19, of the usual character.

40 Interfering is caused by the foot striking in the region of the opposite fetlock, which arises from defective structure or from injury, or a run-down condition, or from defective shoeing. A repetition of blows upon the fetlock causes the part to become swollen, hot, and painful and will eventually lame the horse. Besides this, it often cuts the fetlock and causes bad scarring.

45 50 By the use of this shoe it will be seen that one side, the inner side, is made thicker and heavier than the other and that the curve of the shoe on this heavy side is made

55 to come inside of the normal curve of the horse's hoof. By this means not only will more clearance be given as one foot passes the fetlock of the other but, at the same time, the weight on the inside will tend to 60 drag that side down and, in consequence, will throw the foot out farther as a whole. Furthermore, the other foot will be canted out as it rests upon the ground thus increasing the clearance between the right and left 65 feet.

70 It should be noted that by the construction shown the tendency for the shoe to be worked loose by the horse stamping his feet is done away with since the thickened portion 17 which receives the hardest portion of the blow is not provided with openings 16. These openings 16 are all located in the end portion of the shoe beyond the end of the thickened portion 13. It will thus be 75 seen that since the thickened portion 13 receives the force of the blow that the heads of the nails will not be broken nor will the nails be moved in the hoof, thereby causing the shoe to work loose. It should also be 80 noted that the thickened portion of the shoe starts at a point adjacent the center of the shoe and extends to a point a little over one-half the length of the inner arm. It will, therefore, be seen that the thickened 85 portion is at the point where the greatest wear is and where the horse stamps his feet and that, therefore, the shoe will last longer.

There has thus been provided a simple and efficient device of the kind described and for 90 the purpose specified.

Having thus described the invention, what is claimed as new, is:—

95 In a horse shoe of the class described, a body having one side curved to the curvature of a horse's hoof and the other side flattened to lie within the normal curve of the horse's hoof, and a projection on the underside of the last-mentioned side sloping gently downward from the toe toward 100 the heel and terminating short of the heel in an abrupt shoulder, the thickened portion being unperforated and the end portion being provided with nail receiving openings.

105 In testimony whereof I hereunto affix my signature in presence of two witnesses.

EGIDIO MERCANDELLI.
